DISCHARGER FOR CENTRIFUGAL MACHINES

Joseph Hertrich, Hamilton, Ohio, assignor to The Western States Machine Company, New York, N. Y., a corporation of Utah

Application November 2, 1938, Serial No. 238,390

12 Claims. (Cl. 210—70)

This invention relates to centrifugal apparatus including a new and improved discharger mechanism for use in removing material of varying degrees of hardness from gyratory centrifugal baskets of the type used in sugar mill operation, in such manner as to reduce the danger of damaging the delicate inner linings on the basket wall.

The dischargers used for unloading sugar centrifugals and the like operate with a plowing action. The scraping plate or tip of the discharger shoe enters the revolving annular layer of material on the basket wall and has a tendency to dig more and more into the material. This tendency is due to torque reactions of the basket under discharging loads and to elastic deflection of the discharger mechanism under stresses imposed by the discharging operation. At times the discharger tip is forced against the basket screens with such pressure that the linings are torn or quickly worn out, which of course is objectionable and a source of considerable expense. Improved dischargers, such as those having adjustable stop screws and pivotally attached scraper tips (Roberts, U. S. Patent No. 2,076,516), have eliminated some of the dangers encountered in normal operation, but, a very real danger of tearing out the delicate basket lining still exists particularly when a "hard" load of material is being discharged.

The baskets used in work of this type are of the gyratory suspended type and are susceptible to a certain amount of deflection or swing-out depending directly upon the torque reactions on the basket spindle. This force is in turn directly proportional to the hardness of the layer of material being discharged and to the speed of revolution of the basket. As long as the hardness of the material and the speed of revolution are constant, the basket deflection or swing-out may remain substantially constant and may be well taken care of by the use of an adjustable stop screw limiting the movement of the scraper toward the centrifugal curb, and of a scraper tip pivotably attached to the discharger shoe. When, however, the hardness of the layer or the speed of revolution during discharging are subject to variation, which happens in spite of the greatest precautions, the torque reactions on the basket spindle vary and cause a variable deflection or swing-out of the basket which is not always taken care of by the devices of the prior art. This variation of swing-out, therefore, gives rise to a danger of tearing out the screens or linings of the basket, particularly if the scraper encoun-

ters hard material when the set screw limiting its position relative to the basket curb has been set for a soft material.

The heavy strain placed upon the plow and discharger spindle during the discharging operation also causes an elastic deflection of the discharger mechanism which, like basket swing-out, increases directly with the hardness of the material being discharged and the speed of revolution of the basket. This elastic deflection has objectionable results similar to those caused by the basket swing-out. For example, an increase in the resistance of the material during discharging tends to deflect the discharger shoe toward the adjacent basket wall, in a direction opposite to that taken by the basket when forced to swing out of plumb, thereby adding to the danger of tearing out the screens or linings of the basket.

An object of my invention is to provide in centrifugal apparatus a discharger mechanism which eliminates the objectionable basket swing-out that occurs during the use of conventional discharger mechanisms, and which protects the basket linings from avoidable damage by the tip of the discharger shoe during the discharging operation.

Another object of my invention is to provide centrifugal apparatus having a discharger mechanism associated therewith, in the operation of which forces arising from pressure of the basket contents against the discharger shoe during discharging may be controlled and converted into a useful force which tends to move the basket wall away from the discharger tip, thereby reducing the pressure between the discharger tip and the basket screens when the discharger mechanism undergoes elastic deflection under load.

A further object of this invention is to provide an apparatus by which objectionable pressure between the tip of the discharger shoe and the basket screens may be avoided during discharging irrespective of the resistance of the charge to the plowing action of the shoe.

I have found that the torque reactions or forces acting on the revolving centrifugal basket or basket spindle during discharging, which ordinarily are responsible for excessive pressure between the discharger tip and the basket screens and for consequent damage to the screens, can be controlled and utilized to advantage so as to eliminate much of the cause for such damage. This is accomplished, according to my invention, by providing in association with the centrifugal and its discharger mechanism, a stop or force-con-

trolling means of such nature that the above mentioned torque reactions are counteracted and prevented from causing swinging movement or pressure of the basket wall toward the discharger tip, and of such nature that said reactions create a resultant force on the basket spindle which tends to keep the basket wall and the discharger tip from being pressed too strongly together. Whenever the hardness or resistance of the charge places an unusual stress on the discharger mechanism such as to cause substantial elastic deflection thereof toward the basket wall, this same stress or force reacts on the basket spindle and, through the action of said force-controlling means, there is created a directional force tending to move the adjacent basket wall away from the discharger tip, instead of toward it as in conventional apparatus. In this way, I not only counteract and render harmless the normal tendency of the basket to swing out of plumb during discharging, but I also provide positively acting means for reducing the likelihood of damage to the screens as a result of elastic deflections of the discharger mechanism.

In the accompanying drawings, which illustrate one of several possible forms of construction embodying my invention, Fig. 1 is a vertical section of a centrifugal basket, curb and discharger showing the relative positions of the parts with the discharger shoe inside the basket.

Fig. 2 is a plan view showing a portion of the centrifugal basket in cross-section, with the discharge plow in the position which it occupies upon completion of a discharging operation.

Fig. 3 is a vertical section on the plane of the line indicated by 3—3 of Fig. 2.

Fig. 4 is a fragmentary vertical elevation showing the relative positions of certain parts as viewed from inside the centrifugal basket.

Fig. 5 is a diagram illustrating force conditions which exist in the operation of a conventional centrifugal discharger.

Fig. 6 is a diagram illustrating the force conditions which prevail in the operation of a centrifugal discharger assembly constructed in accordance with my invention.

The apparatus of my invention, includes, in general, a centrifugal basket 12 suspended by a gyratory basket spindle 10, a casing or curb 20 in which the centrifugally expelled liquid is collected, and a discharger mechanism, mounted in fixed position on the curb top including a vertical discharger shaft having a discharger shoe thereon and mounted on a fixed vertical axis for axial and turning movement. As described hereinafter, the apparatus further comprises means for eliminating objectionable torque reactions of the basket and for counteracting elastic deflection of the discharger mechanism by causing a compensating movement or displacement of the basket during a discharging operation.

The discharger mechanism may be of any suitable construction; for example, a mounting bracket 30 provides a hub 32 enclosing a rotatable sleeve 44 which is keyed to the vertical discharger shaft 42, as at 46, in a manner permitting axial sliding movement, but preventing turning movement, of the discharger shaft relative to the sleeve. A handle 71 engages an extension of sleeve 44 and is used to turn the sleeve, the discharger shaft 42 and the discharger shoe or plow 40 mounted thereon during a discharging operation. The shaft 42 is equipped with a gear rack 48 on one side, which is free to move vertically in a slot provided therefor in the bushing 75

44 and which cooperates with a pinion 50 that is keyed to a control shaft 52. In order to secure perfect meshing of the pinion at any position of the rack, the teeth on both pinion and rack are formed with an arcuate shape. The shaft 52 is manually operable by means of a hand wheel 54, keyed to the shaft, and a handle 56 on the wheel. When a use of the discharger has been completed, the hand wheel and pinion are rotated to lift the plowshaft and plow 40 out of the basket and curb, and the plow is then swung to a position overlying and resting upon the top wall 22 of the curb, by actuation of handle 71. When the discharger is to be used, it is swung back over the openings of the basket and curb by actuation of handle 71, and the plow 40 and shaft 42 are lowered into the basket by rotation of hand wheel 54. In the discharging operation, the scraper or tip of the plow 40 is moved outwardly into the wall of material carried by the revolving basket, by movement of handle 71, and the plow is progressively lowered toward the bottom of the basket by turning hand wheel 54 and pinion 50.

The discharger shoe 40, as illustrated in the drawings, is securely attached to the end of the discharger shaft. While it may be constructed in any suitable manner, I prefer to use a construction such as disclosed in U. S. Patent No. 2,076,516 of Eugene Roberts; in, which a resilient tip 41 forms the scraper end of the discharger shoe and is articulated at point 43. A spring 45 holds the tip in normal position, and a stop 49 limits movement of the tip away from normal position, all as described more particularly in said patent.

The top end of the discharger shaft is provided with a shoulder 47 which comes to rest on bushing 44 when the shoe is in its lowermost position, thus preventing the shoe from touching the basket bottom.

A basic and novel feature of the preferred embodiment of my invention resides in the provision, in combination with apparatus of the general type described hereinabove, of means for eliminating objectionable torque reactions of the basket and for reducing the likelihood of damage to the basket screens from elastic deflection of the discharger mechanism by causing a compensating movement or displacement of the adjacent basket wall in a direction away from the discharger tip during the discharging operation. This means is constituted so as to create, in response to pressure of the revolving basket contents against the discharger shoe, a directional force tending to cause movement of the basket wall away from the discharger tip. Such means, for example, may consist of a force-controlling element or stop member which is positioned to engage the basket at an appropriate point during the discharging operation in the manner and with the results described below. In the illustrated embodiment, the force-controlling element is in the form of a roller 64 adapted to engage the basket rim at a point in line with the discharger shaft 42 and the spindle 10. Roller 64 is carried on a slidably bushing 60, mounted on the discharger shaft 42. This bushing is provided with a freely running roller 64 for contacting and exerting a reactionary force on the inner rim, 15 of the top 14 of the centrifugal basket, which overcomes any tendency of the centrifugal basket to swing toward the discharger shaft during the discharging operation. In the illustrated form, a flange 62 is provided on a member 66 secured to the bushing, and when the discharger

plow is within the basket the flange 62 coacts with and rests upon a ledge 68. This locates the bushing on the discharger shaft in such manner that the inner rim 15 of the basket top and the freely running roller 64 lie in the same horizontal plane. The support 68 for member 66 is preferably constructed so as to prevent swaying motion of the discharger shaft when under load, for example, by making it of arcuate shape to engage around member 66 and beneath the flange 62. As the bushing is slidably mounted on the discharger shaft it does not in any way hamper the efficient use of the discharger plow, and its separable connection with the support 68 permits its removal from operating position with the plow when the plow is lifted from within the basket and swung to a position overlying and resting upon the top wall 22 of the curb.

When the discharger shoe is in operating position the face 10 of the handle 71 may be turned until it rests against a stop screw 72 which is screwed into lug 73 of the discharger bracket and is locked by lock nut 74. This screw can be adjusted so that the discharger tip will just barely touch the basket screen when the discharger shaft is turned to its limiting position.

As has been previously stated, during the usual discharging operation, when the plow is digging into the material being discharged, the basket swings in such manner that the basket wall is brought closer to the discharger tip. This is for the most part due to a torque reaction, and to the fact that the centrifugal is of the overhead gyroscopic suspension type to permit safety of operation in the type of work for which it is adapted.

The effect of uncontrolled torque reactions, in an apparatus not embodying the present invention, is illustrated diagrammatically in Fig. 5, where P^1 represents the vector of force caused by pressure of the sugar against the discharger shoe when the discharger is in operation and P^2 represents the vector of force caused by the pressure of sugar on the discharger tip.

Corresponding torque reactions which tend to cause basket swing-out are represented by vectors R^1 and R^2 , the resultant R^3 representing the direction and intensity of the net reactive force that tends to cause swing-out. Moreover, during the discharging operation the plow and discharger spindle are under a heavy strain, and as a result there are elastic deflections in the whole discharger mechanism. The direction of the elastic deflection of the discharger shoe is indicated by D^1 . The extent of such deflection is of course dependent upon P^1 , the pressure exerted on the discharger shoe. In this case it should be noted that the direction of the force causing basket swing-out (R^3) and the direction of the force causing elastic deflection of the discharger shoe (D^1) are almost directly opposite. As a result of this the basket wall or screen adjacent to the shoe tip tends to be moved toward the shoe, and the shoe tip tends to be moved toward the adjacent basket wall, the combined effect being an objectionable pressure of the tip against the basket screen and danger of ripping out the screen.

In Fig. 6 these same fundamental forces are again represented by the same letters, in this case, however, as created in the operation of the illustrated embodiment of my invention, employing a roller 64 mounted on the discharger shaft and engaging the rim 15 of the basket during discharging, as hereinabove described. In this

figure, R^3 , the resultant force arising from the torque reaction, is largely counteracted by the fact that the roller or stop member M contacts the rim of the basket cap in a region where it opposes that force and so prevents inward swinging movement of the basket wall against the shoe tip in response to R^3 . The extent to which M counteracts R^3 , when M is mounted on the discharger shaft, is represented by vector R^4 . It will be observed that R^3 is not completely absorbed by M when M is so positioned; instead, R^3 and R^4 together result in a small reactive force, represented by vector R^5 , in a direction that tends to swing the basket out of plumb in a desirable manner. Any motion of the basket and spindle assembly induced by R^5 takes place in an arc D having an axis near or at the point of contact between M and the basket cap. Such motion, instead of drawing the basket more firmly against the discharger tip, will cause the basket wall to recede therefrom. As the intensity of the reactive forces on the basket assembly increases, due to increased resistance of the material that is being discharged, the value of R^5 , i. e. the force tending to cause alleviating movement of the basket, also increases.

From a study of these two diagrams it can be seen that with an arrangement such as indicated in Fig. 5 the direction of the elastic deflection of the discharger shoe and the swing-out of the basket are opposite, so that the basket is actually pressed toward the tip when the tip is pressed toward the basket; therefore any excessive resistance of the material being discharged has a double tendency to cause objectionable tip pressure against the screen. With an arrangement such as indicated in Fig. 6, however, the reaction of the discharger tip under the elastic deflection of the discharger mechanism is in the same direction as the direction of the basket swing-out. In other words, when the discharger tip deflects toward the basket wall because of an increase in pressure on the shoe or tip, the basket and spindle react under this same pressure and the adjacent basket wall swings away from the tip. Therefore the variation in tip pressure on the basket wall is only the difference between the movement of the tip under the elastic deflection of the discharger mechanism and the swing-out of the basket. As this difference is negligible in a correctly designed discharger, it can be seen that the hardness or variation in hardness of material to be discharged has very little influence on the discharging operation, and that the damaging or destruction of centrifugal linings may be reduced to a minimum by the use of the present invention.

A further feature of my improved construction resides in the fact that the discharger shaft is supported at two points during use, by sleeve 44 and hub 32 and by bushing 60 and ledge 68, instead of by the single support used in prior constructions. This has a beneficial influence on the rigidity of the discharger.

It will be understood that the embodiment of my invention described in this specification and illustrated by the drawings is only a preferable form of the means for eliminating objectionable torque reactions of the basket and for counteracting elastic deflection of the discharger mechanism during the discharging operation and I, therefore, desire a broad interpretation of the invention within the scope and spirit thereof.

and limited only by the claims appended hereinafter.

I claim:

1. In combination, a centrifugal including a suspended gyratory basket, a discharger mechanism including a discharger shaft having a discharger shoe thereon, means mounting said shaft on a fixed vertical axis for axial and turning movement whereby to move the shoe into material carried in said basket while the same is revolving to discharge the material therefrom, and means mounted on the discharger shaft in position to engage an inner circular edge of the revolving basket at a substantially fixed point adjacent to said shaft throughout a discharging operation, said last recited means being operative to compensate for elastic deflection of the discharger mechanism under load by causing a compensating movement of the basket wall away from said shoe in response to pressure of the basket contents against said shoe, whereby to prevent convergence of the tip of the shoe and the adjacent basket wall because of variations in the hardness of the material being discharged.

2. In combination with a centrifugal including a suspended gyratory basket and a discharger shaft carrying a discharger shoe adjacent its lower end, means mounting said discharger shaft on a fixed vertical axis for axial and turning movement whereby to lower the shoe into the basket and to move the shoe into the contents of the basket while the same is revolving, a bushing slidably mounted on the discharger shaft, a roller carried by said bushing, and means for holding said bushing and roller so that the roller engages the inner rim of the basket top at a fixed point adjacent said shaft when the discharger shoe is lowered to operating position.

3. In combination, a centrifugal including a suspended gyratory basket and a surrounding curb, a discharger mechanism mounted on said curb including a vertical discharger shaft and a discharger shoe thereon adapted to be moved into the contents of said basket when the shaft is lowered into the basket and turned to discharge such contents, a bushing slidably mounted on the discharger shaft, a roller carried by said bushing, and cooperating means on said curb and said bushing for holding said roller in contact with the revolving basket rim at a fixed point adjacent said shaft when the discharger shoe is lowered to operating position.

4. Centrifugal apparatus comprising a suspended gyratory basket and a surrounding stationary curb, a discharger mechanism mounted on said curb including a vertical discharger shaft and a discharger shoe extending radially therefrom and adapted to discharge the contents of said basket when the shaft is lowered and turned to direct the shoe into the revolving basket contents, and roller means mounted on said discharger shaft so as to engage the inner rim of the revolving basket top at a fixed location during a discharging operation and operative during such operation to convert reactive forces on said basket, arising from the resistance of the revolving basket contents to the plowing action of said shoe, into a directional force tending to displace the revolving basket wall away from the tip of said shoe.

5. Centrifugal apparatus comprising a suspended gyratory basket and a surrounding stationary curb, a discharger mechanism mounted on said curb including a vertical discharger shaft and a discharger shoe extending radially

therefrom and adapted to discharge the contents of the basket when the shaft is lowered and turned to direct the shoe into the revolving basket contents, and a roller on said discharger shaft positioned to engage an inwardly facing circular edge on the revolving basket during a discharging operation at a point radially in line with the axis of said basket and said shaft.

6. In a discharger mechanism for a gyratory centrifugal machine, a discharger shaft adapted to extend vertically through the opening in the top of the centrifugal basket, a discharger shoe carried on the lower end of said shaft and adapted to be turned by said shaft into the contents of the centrifugal basket, and roller means secured to said shaft above said shoe and adapted to contact the inner rim of the revolving basket top adjacent said shaft when the discharger is in operative position.

7. In a discharger mechanism for a gyratory centrifugal machine, a discharger shaft adapted to extend vertically through the opening in the top of the centrifugal basket, a discharger shoe carried on the lower end of said shaft and adapted to be turned by said shaft into the contents of the centrifugal basket, a bushing slidably keyed to said shaft above said shoe, a roller mounted on said bushing and adapted to contact the inner rim of the revolving basket top adjacent said shaft when the discharger is in operative position, and means for holding said bushing and roller in line with the inner rim of the basket top when the discharger is in operative position.

8. In combination, a centrifugal including a gyratory basket, a discharger mechanism including a vertical discharger shaft carrying a discharger shoe adjacent its lower end, means mounting said shaft on a fixed vertical axis for axial and turning movement whereby to move said shoe into and to discharge the contents of the basket while the same is revolving, and means located in a fixed position on said shaft during a discharging operation to engage the revolving basket during such operation at a fixed location disposed angularly away from a diametrical vertical plane passing through the axis of said basket and the tip of said shoe, so as to prevent movement of the basket in radial direction toward said discharger shaft in reaction to the pressure of the basket contents against said shoe, said last recited means also being operative during a discharging operation to convert excessive forces on said basket, arising from such pressure, into a force tending to cause swinging movement of the basket wall away from the tip of said shoe, whereby to minimize objectionable pressure between said tip and the adjacent basket wall through elastic deflection of the discharger mechanism.

9. Centrifugal apparatus comprising, in combination, a suspended gyratory spindle and basket assembly, a discharger mechanism including a discharger shaft having a discharger shoe thereon, means mounting said shaft for axial and turning movement on a fixed vertical axis whereby to move said shoe into and to discharge the contents of the basket while said assembly is revolved, and a stop member positioned and maintained at a fixed location during a discharging operation whereat said member engages the revolving assembly and opposes the resultant of reactive forces on the assembly that arise from the plowing action of the shoe and so prevents swinging movement of the revolving basket wall.

against the tip of the shoe in response to such forces, said member engaging said assembly only within a limited angular region disposed angularly away from a diametrical vertical plane passing through said tip and the axis of said spindle.

10. In centrifugal apparatus comprising a suspended gyratory spindle and basket assembly and a discharger mechanism including a discharger shaft having a discharger shoe thereon and means mounting said shaft for axial and turning movement on a fixed vertical axis whereby to move said shoe into and to discharge the contents of the basket while said assembly is revolved, a stop member positioned at a fixed location during a discharging operation whereat said member engages the revolving assembly, opposes the resultant of reactive forces on the assembly that arise from the plowing action of the shoe and so prevents swinging movement of the revolving basket wall against the tip of the shoe in response to such forces, and means operated as a result of moving said shaft axially to move said shoe into the basket for positioning and maintaining said member at said location, the place of engagement of said member with said assembly being within a limited angular region disposed angularly away from a diametrical vertical plane passing through said tip and the axis of said spindle.

11. Centrifugal apparatus comprising, in combination, a suspended gyratory basket and spindle assembly, a discharger mechanism including a discharger shaft having a discharger shoe thereon, means mounting said shaft for axial and turning movement on a fixed vertical axis whereby to move said shoe into and to discharge the contents of the basket while said assembly is revolved, and a stop member positioned

and maintained at a fixed location during a discharging operation whereat said member engages the revolving assembly, opposes the resultant of reactive forces on the assembly that arise from the plowing action of the shoe, so preventing swinging movement of the revolving basket wall against the tip of the shoe in response to such forces, and converts such forces into a directional force tending to displace the revolving basket wall away from said tip, said member engaging said assembly only within a limited angular region disposed angularly away from a diametrical vertical plane passing through said tip and the axis of said spindle.

15. 12. Centrifugal apparatus comprising, in combination, a suspended gyratory basket and spindle assembly, a discharger mechanism including a discharger shaft having a discharger shoe thereon, means mounting said shaft for axial and turning movement on a fixed vertical axis whereby to move said shoe into and to discharge the contents of the basket while said assembly is revolved, and a stop member positioned and maintained at a fixed location during a discharging operation whereat said member engages the revolving basket, opposes the resultant of reactive forces on the assembly that arise from the plowing action of the shoe, so preventing swinging movement of the revolving basket wall

20 against the tip of the shoe in response to such forces, and converts such forces into a directional force tending to displace the revolving basket wall away from said tip, said member engaging said basket only within a limited angular region disposed angularly away from a diametrical vertical plane passing through said tip and the axis of said spindle.
